UNITED STATES PATENT OFFICE.

FRANK S. ELY, OF MERIDEN, CONNECTICUT, ASSIGNOR TO C. ROGERS & BROS., OF SAME PLACE.

DESIGN FOR COFFIN-TRIMMINGS.

SPECIFICATION forming part of Design No. 17,793, dated October 18, 1887.

Application filed August 15, 1887. Serial No. 247,016. Term of patent 14 years.

To all whom it may concern:

Be it known that I, FRANK S. ELY, of Meriden, in the county of New Haven and State of Connecticut, have invented a new Design for Coffin-Trimmings; and I do hereby declare the following, when taken in connection with accompanying drawing and the letters of reference marked thereon, to be a full, clear, and exact description of the same, and which said drawing constitutes part of this specification, and represents a face view.

This invention relates to a design for coffin-trimmings, such as screw-heads, lid-lifters, name-plates, motto-plates, &c.; and it consists in the representation of a bird holding a streamer, which streamer extends from the back side of the bird through the beak, around the front downward to the rear, and returned below the wings again to the back side, as hereinafter described.

The design as illustrated is for a name or motto plate. The bird is represented with

wings spread in hovering position, holding in its beak a streamer, the streamer extending through the beak of the bird from the back side around the front and downward to the rear, returned below the wings to the back side. As a screw or lifter the representation of a base is provided, as shown in broken lines, which gives the appearance of the bird just lighting upon the base.

I claim—

The herein-described design for coffin-trimmings, consisting of the representation of a bird, its wings spread, with the representation of a streamer extending from the back side of the bird through its beak forward and downward to the rear, returned again below the wings to the back side, as shown in the accompanying illustration.

FRANK S. ELY.
